UNITED STATES PATENT OFFICE.

JOHN F. WAY, OF YANTIC, CONNECTICUT.

STARTING GAUGE FOR LOOMS.

Application filed December 22, 1922. Serial No. 608,488.

To all whom it may concern:

Be it known that I, JOHN F. WAY, a citizen of the United States, residing at Yantic, in the county of New London and 5 State of Connecticut, have invented certain new and useful Improvements in Starting Gauges for Looms; and I do hereby declare the following to be a full, clear, and exact description of the invention, such as will enable others skilled in the art to which it 10 appertains to make and use the same.

This invention relates to a starting gauge for looms.

One object is to provide a construction 15 which has means applicable to a loom and adapted to be set to indicate the point or place at which the batten strikes the particular cloth being woven and to then be removed to enable removal of picks to over- 20 come a fault in the cloth or fabric and to be replaced after correction of the fault; a construction in which such means is yieldable under movement of the cloth with respect 25 to such point and to a zero indication after removal of faulty picks so as to accurately 30 gauge the starting point for subsequent weaving, to the end that a "heavy place" or a "light place" in the fabric, as frequently occurs incidental to loosening of 35 the cloth by operation of the take-up gear and pulling the cloth back and the guess work in the amount of filling or number of picks removed to correct the fault, is overcome.

35 Various additional objects and advantages will become apparent from a consideration of the description following taken in connection with accompanying drawings illustrating one operative embodiment thereof.

40 In said drawings:—

Figure 1 is a fragmentary vertical section showing a loom fragmentarily and with the invention in place in side elevation;

45 Figure 2 is a plan view showing a loom fragmentarily and the invention in place;

Figure 3 is an enlarged plan view partly broken away of the gauge;

Figure 4 is a section on line 4—4 of Figure 3;

50 Figure 5 is a section on line 5—5 of Figure 3, and

Figure 6 is a section on the line 6—6 of Figure 4.

Like reference characters designate like 55 or similar parts in the different views.

To facilitate an understanding of the in-

vention, a loom has been conventionally and fragmentarily shown of which A is the breast beam, B is the batten, C the fabric, D the warp threads and E the fell or inner 60 extremity of the fabric. The winding or take up rolls are at F.

The invention comprises a bracket or base of metal or other suitable material designated 10 on which a follower 11 is slidably 65 mounted and from which one or more tines 12 depend intermediate and below the warp threads D and engage against the fabric at the fell E. At the opposite end, an anchoring lug 13 is adjustably secured to the base 70 10 as by means of adjustable bolts or the like 14 passing through elongated slots 15, one in an upper flange 16 of the lug 13 and the other in the base 10. Said bolts also pass through holes 17 in said flange 16 and 75 base 10 and have winged nuts 16' thereon to facilitate finger manipulation. A readily adjustable connection is thus provided between the anchoring lug 13 and the base.

The follower 11 may be a metallic plate 80 and have one or more elongated slots 18 through which suitable bolts 19, secured to the base 10 pass. The rearward end of the follower 11 is embraced by a clip at 20 which by means of rivets or the like 22 is 85 securely fastened against the follower. Said tines 12 are the free ends of U-shaped wire strands 23 whose bight or bridge portions 24 surround the rivets 22 and are clinched in place thereby. Said tines 12 90 intermediate their ends are bent at a right angle as shown to accommodate positioning and fastening and they pass through holes 25 in the clip 20. The tines 12 are normally urged toward the anchoring lug 13 by 95 means of a contractile coil spring 26 fastened by means of a hook 27 to the follower plate 11 and by means of a hook 28 to an anchor bolt 29 on the base 10.

Disposed above the base plate 10 is a dial 100 30 of any suitable material and having one or more suitable calibrations or indications thereon, particularly a zero point as at 31. This dial in any suitable manner, may be secured to a top plate 32 which forms part 105 of a supporting frame completed by posts 33 rising from a bottom plate 34 fastened in any suitable manner on the base plate 10. Journaled in the plates 32 and 34 and extending above the dial 30 is a shaft 35. 110 Movable over the dial 30 is an indicator arm 36 extending rigidly from a hub 37 through

which shaft 35 is passed and which is clamped between nuts as at 38 threaded on the shaft 35. In view of the adjustable connection of the indicator arm 36 to shaft 35, the arm may be moved independently of the shaft to set it at the zero point 31 irrespective of the position of shaft 35.

The shaft 35 is adapted to be rotated or turned through sliding movement of the follower 11. To this end, a shaft 39 is journaled in the plates 32 and 34 having a gear wheel 40 rigid thereon and a substantially U-shaped crank 41 riveted or otherwise fastened as at 42 through one of its arms to said gear wheel and with its other or lower arm slotted as at 43. A pin 44 rises from an end extension 45 of the follower 11 and is disposed in the slot 43. Said gear wheel 40 meshes with a smaller gear wheel or pinion 46 rigid on the shaft 35.

Suitable guide pins 47, having heads 48 to overlap the slide or follower 11 may be provided, and they as well as bolt 19 may have nuts 49 disposed intermediate the same and the plate 10 to prevent binding of the slide or follower against such plate.

In use, during the weaving operation, in the event of a fault occurring in the cloth, operation of the loom as usual is brought to a stop. The gauge is then applied as shown in the drawing. The correct adjustment of the anchor lug 13 with respect to the follower 11 is obtained through manipulation of the nuts 16'. The parts are preferably applied with such nuts loosened and the nuts are thereupon tightened. Nuts 38 and indicator 36 are then adjusted to set the indicator 36 at zero point 31. Thereupon the gauge is removed. The fault is then corrected as usual by loosening the cloth through the medium of the take up gear. After the proper number of picks have been removed, the cloth and warps are pulled back from the means F to an extent to compensate for the picks removed. This is under present conditions a mere matter of guesswork. With my improved gauge, after the picks have been removed, the gauge may be repositioned on the loom as shown in the drawings and the warp and cloth pulled from the rolls F sufficiently to enable the fell E to engage the tines 12 with the indicator 36 at zero point 31. In the event the cloth has not been pulled sufficiently from the rolls F, the indicator 36 will be on one side of zero point 31 while if the cloth has been pulled too far, it will be on the other side of zero point 31, thus indicating to the operator that further adjustment of the cloth is necessary and showing the extent of adjustment. When such tines 12 are in engagement with the fell E and the indicator 36 registers with the zero point 31, the operator will know that the fell is in proper

position for subsequent weaving and will thereupon place the loom in condition for further weaving after removing the gauge. Thus it is not a matter of guesswork in showing the exact starting point for subsequent weaving since the invention positively positions the fell accurately for subsequent weaving or engagement by batten B without producing "heavy places" or "light places."

I claim as my invention:

1. A starter gauge for looms including a base, a retractile follower slidable on said base engageable with so as to be positioned by the line of the cloth, indicating means on said base operable for setting at zero according to the position of said line, and means to actuate said indicator means through movement of said follower.

2. A starter gauge for looms including a base plate, an anchor member thereon adjacent one end and extending therefrom to engage the breast beam of a loom, a follower slidable on said base plate and having a tine to engage the line of the cloth, a return spring for said follower and indicating means on the base operable through movement of the follower.

3. A starter gauge for looms including a base plate, an anchor member thereon adjacent one end and extending therefrom to engage the breast beam of a loom, a follower slidable on said base plate and having a tine to engage the line of the cloth, a return spring for said follower and indicating means on the base operable through movement of the follower, including a gear wheel, a shaft on which said gear wheel is mounted, a crank movable with said gear wheel, a pin extending from the follower and into said crank, an indicator shaft, a pinion on said indicator shaft in mesh with said gear wheel, an indicator on said shaft, and a dial to cooperate with said indicator.

4. A starter gauge for looms including a base, an anchor lug extensibly connected to said base, a follower slidable on said base having depending tines engageable and adapted to move with the line of the cloth, a frame on said base having a top and a bottom plate and posts intermediate them, a dial on the top plate, a shaft journaled in said plate, an indicator on said shaft cooperating with the dial, a pinion on said shaft, a second shaft journaled in said top and bottom plates, a gear wheel on the second shaft in mesh with said pinion, a crank rigid with said gear wheel having an elongated slot, a pin extending from the follower into said slot, and a return spring connected to said follower and to said base.

5. A starter gauge for a loom having a base for removable application to the loom, a follower mounted thereon and adapted for engagement with the line of the cloth, indi-

cator means on said base operable by the follower and adapted to be set at zero according to the position of said line, and an anchor lug engageable with the loom depending from and adjustably mounted on the base to facilitate positioning of the follower.

6. A starter gauge for a loom having a 5
slidable follower adapted for engagement
with the line of the cloth, a shaft turnable
by said movement of the follower, an indicator
on said shaft, and means to vary the
position of said indicator independently of
and with respect to said shaft.
- 10 7. A starter gauge for a loom having a
15

base, a dial on said base, a follower slidable on said base adapted for engagement with the line of the cloth, a shaft turnable through said movement of the follower, an indicator on said shaft movable with respect 20
to said dial, and means operable to vary the position of said indicator independently of the shaft according to the position of said line.

In testimony whereof I affix my signature 25
in presence of two witnesses.
